[57] CLAIM

The ornamental design for a Retrieval Cartridge, as shown and described.

DESCRIPTION

FIG. 1 is a top perspective view of a Retrieval Cartridge showing my new design.

FIG. 2 is a bottom perspective view thereof.

FIG. 3 is a side view thereof.

FIG. 4 is a front side view thereof.

FIG. 5 is a rear view thereof.

FIG. 6 is a opposite side view thereof.

FIG. 7 is a top view thereof; and,

FIG. 8 is a bottom view thereof.
